UNITED STATES PATENT OFFICE.

ROBERT S. NOAH, OF ANNAPOLIS, MARYLAND, ASSIGNOR TO HENRY B. REINHARDT,
TRUSTEE, OF ROLAND PARK, MARYLAND.

SUBMARINE GUN-TURRET.

1,296,688.

Specification of Letters Patent. Patented Mar. 11, 1919.

Application filed December 13, 1916. Serial No. 136,791.

To all whom it may concern:

Be it known that I, ROBERT S. NOAH, a citizen of the United States, residing at Annapolis, in the county of Anne Arundel and State of Maryland, have invented certain new and useful Improvements in Submarine Gun-Turrets, of which the following is a specification.

This invention relates to improvements in a sea-going vessel of the submersible type, and has particular reference to providing such vessels with a revoluble gun-turret and with means that shall have the capability of raising the turret to a position above the deck of the vessel when a gun in the turret is about to be fired, and when there is no occasion for using the gun the same means will give the capability of lowering both the gun-turret and gun into the hull of the vessel where they will be hid from the view of persons afloat on any vessel that may be in the vicinity.

The inventive idea therefore consists of providing means whereby a submarine vessel may have mounted a revoluble gun-turret that will lower and disappear from sight.

The invention is illustrated in the accompanying drawings in which—

Figure 1, is a vertical section of part of a submarine vessel, and the revoluble gun-turret, the latter being shown lowered below the deck of the vessel as when it has disappeared.

Fig. 2, is a horizontal cross-section through the revoluble turret and shows the gun, all the parts are drawn to a larger scale, and have the position they occupy when said turret and gun are lowered.

Fig. 3, is a horizontal section view of the same parts seen in Fig. 2, but the turret has been elevated and the gun projects through the embrasure in position for firing.

Referring to the drawings, the numeral 6, designates the bottom of the hull; on top 45 and at the highest part of the hull is an upper deck, 9, and next below is a ceiling, 11, while the space between said deck and ceiling constitutes a closed air-chamber, 10, which is thus formed within the top of the 50 vessel's hull. The lowermost deck, 19, of the vessel, in the present instance, is the floor of the engine room. The intermediate deck, 18, separates the lower compartments, 16, from the upper compartments, 17. A space 55 20, is shown between the lower deck, 19,

and the vessel-bottom, 6, to contain ballast-water and to receive sea-water that is required to cause the vessel to submerge.

It will be understood that the particular interior construction of the decks, bulkheads, and other parts of a submarine are unimportant, as such parts may be planned differently from what is shown in the drawing.

The present invention includes a vertical 65 cylinder, 12, of any preferred construction and the same has fixed position within the hull and extends through the decks of the submarine vessel. This cylinder has a closed lower end, 13, and its upper end 14, is open 70 and the packing seat, 29, in the upper end in the present instance, is flush with the top of the upper deck.

The circular wall of the cylinder has 75 openings, 21, 22, which may communicate with the lower and upper compartments, 16, and 17, respectively; doors, 23 are provided to close said cylinder openings.

The turret, 15, is circular and fits movably within the upper part of the vertical 80 cylinder, 12; it has a bottom, 26, a closed and slightly convex top, 27, and a flange 28, around the top projects horizontally and when the turret is in its lowered position, as shown in Fig. 1, said top flange, 28, contacts 85 with the packing seat, 29, positioned at the top end of the cylinder, and by the flange pressing down thereon a water-tight joint is formed which excludes sea-water.

The turret has a leg, 43, which projects 90 downward from the bottom, 26; the lower end of this leg is rounded and sets in a step-bearing, 44, on the elevator piston; said leg partly supports the turret, and also is a part 95 of the mechanical means to cause the turret to revolve, as will be presently described. The turret has an embrasure, 30, in its wall which is closed by a hinged door, 31, swinging on the inner side of the turret. This door must be opened to permit the end 32, 100 of the gun to be run out through the embrasure.

A hollow piston, 24, fits within the cylinder, 12, below the turret, 15, and on its exterior circumference the piston has packing 105 rings, 25, that contact with the bored surface of the cylinder. The hollow piston has a closed bottom, 45, and a top, 46. On the upper side of this top is a circular groove, 47, and the bottom of the revoluble turret 110

also has a corresponding circular groove, and hardened steel balls, 48, are in the two grooves. It will be seen that most of the weight of the turret and its gun is supported by the anti-friction balls, 48, though the leg, 43, serves also as a support. The step-bearing, 44, is in the hollow piston, and the top, 46, of the latter has a hole through which said leg, 43, extends and also revolves. To effect the revolution of the turret, the leg carries a spirally-toothed wheel, 49, and an endless screw, 50, gears therewith; power may be obtained from the engine or otherwise.

15 One or more openings, 51, are provided in the bottom, 26, of the turret and these will register with stairs, 52, carried by the piston elevator, 24, to enable men to pass up and down.

20 The gun is mounted on a carriage, 53, which moves on track-rails 54, extending diametrically across the bottom 26, of the turret and a rack-bar, 55, fixed on said bottom between the rails is engaged by a toothed 25 wheel on the gun-carriage, which wheel moves the gun.

In Fig. 1, the broken lines above the top of the view show the outline shape of the turret 15, and indicate the position the turret and gun will have above deck when the turret has been raised in readiness to fire the gun.

When the turret is in the lowered position shown in Fig. 1, it will be understood to have 35 disappeared from view.

It will be seen that the bottom of the gun-turret has an inverted circular groove, and the top of the elevator, 24, has a corresponding circular groove, 37, and that balls, 48, are 40 positioned between the two circular grooves, and thereby the gun-turret is supported and may be revolved independently of any movement of the piston elevator, and also elevated, without regard to whether the gun-turret is or is not inclosed by the walls of 45 a vertical cylinder, as shown in Fig. 1. By this description it is meant that the hollow piston, 24, is an elevator that raises the gun-turret vertically and also allows said turret 50 to move downwardly.

The horizontal broken line *s. s.* extending above the structure in Fig. 1, indicates the approximate relative position of the surface of the sea-water and the top deck of the 55 submarine when the vessel is afloat at or near the surface though by pumping out more water the vessel may of course be raised higher.

To raise the turret from its disappeared 60 position I have provided a pump and engine to employ fluid-pressure, see Fig. 1.

A pump, 37, rests on the lower deck, 19,

and at each of two opposite sides of the pump is an attached pipe, one of which is designated, 38, and the other, 39; these two pipes are discharge pipes and pass through the lower deck 19, and open into the storage-water, or bilge-water, space, 20. Each of these pipes has a cut-off valve, 40. Attached also to opposite sides of the pump, 37, is a pipe designated at one side 41, and at the other side designated, 42. These last named pipes pass through the lower deck and extend along the water space, 20, and then pass upward through the bottom, 13, of the cylinder below the closed lower end, 45, of the movable piston, 24. These are the fluid-pressure pipes. Each pipe of the two last named has a cut-off valve, 43. By manually operating the several valves the turret and gun may be raised or lowered by the power of 75 the pump, 37.

Having described my invention what I claim and desire to secure by United States Letters Patent is,—

1. In a submarine vessel, the combination 85 of a hull; a cylinder having fixed position vertically within the hull; a piston having a vertical reciprocating movement, and provided with a step-bearing; a gun-support movable in the cylinder and having a leg 90 which sets in said step-bearing; and means carried by the vertically-moving piston to impart revoluble movement to said gun-support.

2. In a submarine vessel, the combination 95 of a hull; a cylinder having fixed position vertically within the hull; a piston having a vertical reciprocating movement and provided with a step-bearing; a gun-support movable in the cylinder and having a leg 100 which sets in said step-bearing; and means carried by the piston and connected with the said leg for revolving the gun-support.

3. In a submarine vessel, the combination 105 of a hull; a cylinder having fixed position vertically within the hull; a piston having a vertical reciprocating movement within the lower part of said fixed cylinder; a gun-turret having circular inclosing walls and carried upon the said piston and fitting so as 110 to move both vertically and revolubly within the upper part of said fixed cylinder, whereby the circular gun-turret may be elevated above the hull and deck and then revolved, and also lowered below the deck and concealed in the fixed cylinder.

In testimony whereof I affix my signature in the presence of two witnesses.

ROBERT S. NOAH.
